CLAIM

The ornamental design for an architectural panel with wood grain and clustered cutout, as shown and described.

DESCRIPTION

FIG. 1 is a front perspective view of an architectural panel with wood grain and clustered cutout showing my new design in use condition;

FIG. 2 is an enlarged front perspective view thereof;

FIG. 3 is a front elevational view thereof, the rear elevational view being a mirror image thereof;

FIG. 4 is a left elevational cross-sectional view thereof taken along line 4—4 of FIG. 3;

FIG. 5 is a right elevational cross-sectional view thereof taken along line 5—5 of FIG. 3;

FIG. 6 is a top plan cross-sectional view thereof taken along line 6—6 of FIG. 3; and,

FIG. 7 is a bottom plan cross-sectional view thereof taken along line 7—7 of FIG. 3.

The long dash short dash broken line showing of a wall structure in FIGS. 1 and 2 is included for the purpose of illustrating environmental structure and forms no part of the claimed design. The short dash broken line shown in FIGS. 1-7 is included for the purpose of illustrating the boundary of the architectural panel with wood grain and clustered cutout and forms no part of the claimed design.
